TIlt HEAD FOR A CAMERA TRIPOD OR THE LIKE

Adolph R. Schnase, Norco, Calif., assignor to Davidson Optronics, Inc., West Covina, Calif., a corporation of California

Filed Mar. 16, 1966, Ser. No. 1,494

Term of patent 14 years

(Cl. D61—1)

FIG. 1 is a side, top and front perspective view of a tilt head for a camera tripod or the like, showing my new design;

FIG. 2 is a fragmentary rear elevational view partly in cross-section taken on line 2—2 in FIG. 1, a portion of the handle being omitted for convenience in illustration;

FIG. 3 is a top plan view; and

FIG. 4 is a fragmentary opposite side elevational view thereof, looking in the direction of the arrow 4 in FIG. 2, a portion of the handle having been omitted for convenience in illustration.

The broken line fragmentary showing of a representative tripod is for illustrative purposes only.

I claim:

The ornamental design for a tilt head for a camera tripod or the like, substantially as shown and described.
